TWO-POSITION VARIABLE PITCH PROPELLER

Charles I. Lathrem, Quebec, Quebec, Canada, assignor to Canadian Car and Foundry Company Limited, Montreal, Quebec, Canada, a corporation of Canada

Application March 10, 1945, Serial No. 582,005

8 Claims. (Cl. 170—160.32)

1

This invention relates to airplane propellers and more particularly to that type sometimes called changeable or variable pitch propellers.

The invention provides propellers which may be adjusted to operate at a predetermined fine pitch or to operate at a predetermined coarse pitch. Counterweights attached to the propeller blades are utilized to adjust the propeller to one position and a hydraulic motor within the propeller hub is utilized to adjust the propeller to the other position.

According to one form of device embodying the invention a hollow hub having radially extending hollow arms to support the root ends of the propeller blades for rotation, also serves as a reservoir for hydraulic fluid. A fluid pump is mounted in the hub. By means of this pump, which may be caused to operate in response to rotation of the propeller, the fluid is caused to act upon an hydraulic motor within the hub. This motor has a piston slideable along a hub insert; the hub insert serving also to mount the propeller on the engine drive shaft. By means of counterweights mounted on the blades the blades may be caused to assume coarse pitch position and by means of the hydraulic motor the force of the counterweights may be overcome and the propeller blades caused to assume fine pitch position. Suitable levers are provided to connect the coaxially sliding piston with the root ends of the blades to translate axial movement of the piston to angular rotation of the blades about their longitudinal axes and vice versa. Suitable stops are provided to retain the blades in predetermined fine pitch position when the piston is urged under the influence of hydraulic pressure in a direction opposed to the force of the counterweights and to retain the blades in predetermined coarse pitch position when the piston is urged in the opposite direction under the influence of the counterweights.

Although the novel features which are believed to be characteristic of the invention will be particularly pointed out in the claims appended hereto, the invention itself, as to its objects and advantages, and the manner in which it may be carried out, may be better understood by referring to the following description taken in connection with the accompanying drawings forming a part hereof, in which:

Fig. 1 is a cross-section of the propeller assembly according to the invention mounted on the drive shaft of an airplane engine on line 1—1 of Fig. 2;

2

Fig. 2 is a view of the propeller on line 2—2 of Fig. 1;

Fig. 3 is a view in section on line 3—3 of Fig. 1;

Fig. 4 is a view on line 4—4 of Fig. 1;

Fig. 5 is a view on line 5—5 of Fig. 1;

Fig. 6 is a plan view of the pump unit in the hub to larger scale;

Fig. 7 is a view in elevation of the pump taken on line 1—1 of Fig. 6;

Fig. 8 is a view in section of the pump on line 8—8 of Fig. 7; and

Fig. 9 is a view in horizontal section of the friction wheel, its shaft and housing.

The propeller shown in the drawings comprises, in general, a hub 10, propeller blades 11, 11a and a hollow insert 12 serving to mount the propeller on the engine drive shaft 13. The drive shaft extends through a bracket 14 fixed to the airplane engine.

The hub, designated generally by reference character 10, has a hub barrel 15 of generally cylindrical shape from which extend hollow arms 16 and 16a radially from the hub barrel. Inasmuch as each of arms 16 and 16a and the blade mounting is of similar construction, only one is described; it being apparent that parts indicated by reference characters with sub-letter "a" are similar to those parts having the same reference character without sub-letters.

The root end of propeller blade 11 is mounted in a ferrule 17 having a cylindrical wall portion 18, and a base portion 19 through which extend lag bolts 20 to secure the blade to the ferrule. The ferrule, and hence the blade 11, is mounted for rotation about the blade axis 21.

The ferrule 17 is mounted in bearings 22 and 23 of radial thrust type, each comprising balls 24 mounted in an inner ring race 25 and an outer ring race 26. The inner bearing 23 rests upon an annular flange 51 of the hollow arm 16 and on a split ring 52 on the ferrule 17. An annular flange 27 on the ferrule 17 maintains the bearings 22 and 23 in spaced relation and serves to take the thrust when the propeller is rotated

about its axis of rotation 28. A threaded blade retention nut 29 maintains the bearings in place. A packing ring 30 serves to prevent hydraulic fluid, later to be described, from leaking out of the hub. A nut retention plate 31 having radially extending projections registering with slots 32 in the hub arm is secured to hub retention nut 29 by screws 33.

The hollow hub insert 12 is mounted in the hub and secured thereto in suitable manner, as by welding. It is in general of cylindrical shape

and has a bore 41 which may be tapered slightly from the rear (that is, the end nearest the engine) toward the front end. Its interior surface has splines 34 and grooves 35 which register with corresponding splines and grooves on the exterior surface of the drive shaft. The drive shaft 13 has a bore 36.

The inner end of hub insert 12 is flared and the flared portion 37 has a tapered interior surface 38. The outer end of the insert also has a flared portion 39 having a tapered interior surface 40 tapering inwardly toward the rear. When the propeller is mounted on the engine drive shaft 13 a spacer ring 42 abuts the shaft nut 9. A rear cone ring 43 abuts the spacer 42, and the interior surface 38 of the insert flared portion 37 engages the exterior tapered surface 44 of the cone ring 43. A split front cone ring 45 fitting around the forward end of the drive shaft 13 has a tapered surface 46 engaging the interior tapered surface 40 of the insert flared portion 39. This split cone ring 45 has an outwardly extending cylindrical wall portion 47, having an annular groove 48.

To secure the propeller to the drive shaft 13 there is provided an internally threaded shaft nut 49, the threads of which engage corresponding external threads on the shaft. An annular flange 50 on the nut 49 fits into groove 48. Hence, when the nut 49 is tightened and adjusted the propeller is made fast to the engine shaft. When the propeller is thus made fast to the shaft, a shaft nut pin 53 extending through registering apertures in the shaft nut and engine shaft prevent the nut from turning on the shaft, thus to maintain the propeller properly secured to the engine drive shaft, notwithstanding vibrational or other forces which may tend to rotate the nut on the shaft.

The exterior cylindrical surface of the hub insert 12 is provided with spaced annular flanges or bosses 60 and 61, the boss 60 for convenience of description being designated as the front boss, and boss 61, as the rear boss. At their outer peripheries these annular bosses have machined or smooth surfaces 62 and 63. Each boss on the inside is hollowed out to provide in effect annular spaces 64 and 65. The peripheral exterior surface 66 of the insert between the spaced bosses 60 and 61 is also machined or smooth. A split ring piston, designated generally by reference character 67, comprises two complementary half sections each of similar construction. When assembled on the insert, the piston may be said to comprise an annular piston which is an inwardly extending portion 68 within a sleeve 69. The annular or ring piston 68 engages the exterior surface 66 of the insert and the sleeve portion 69 of piston 67 has an interior surface 70 which is machined or smooth and engages the peripheral surfaces 62 and 63 of the annular bosses 60 and 61. The piston 67 is slideable coaxially along the insert 12.

For convenience of assembly, the piston is made up of two complementary half sections 71 and 71a (see Fig. 2). Since both are similar in construction only one is described. Half section 71 has a lug 72 having a bore 73 which is internally threaded and has, on the opposite side, a lug 74 having an internal bore 75. Half section 71a is similar and has corresponding but complementary bosses and bores. When fitted together in complementary fashion around the insert with the sleeve 69 of the piston 67 engaging the outer surfaces of the annular bosses 60

and 61, the bore 73 registers with bore 75a and bore 75 with bore 73a. Pins 76 and 76a each having a threaded end, a nut portion and also a projecting slot-engaging portion, secure the two half sections 71 and 71a together. As shown in Fig. 2 pin 76 is externally threaded at one end to engage the threads of lug 72a. An integral nut 77 provides a convenient means to tighten the pin. The outer end of the pin has a slot-engaging portion 78 disposed within the slot 79 of lever 80, described in further detail hereinafter. Pin 76a is of similar construction and corresponding parts are designated by the same reference characters with the sub-letter "a."

15 The annular piston portion 68, which may be referred to for convenience of description as a ring piston, comprising the two half sections, is provided with an annular groove 81 to accommodate a packing ring 82. The packing ring 20 may be held snugly against the cylindrical surface 66 by means of a helical spring 83 within the groove and extending around the packing ring.

25 Boss 60 is provided with a port 84 connecting with the interior annular space 64 and boss 61 is provided with a port 86 connecting with the interior of annular space 65. As described in further detail hereinafter, hydraulic fluid under 30 pressure may be routed through the port 84 to move the ring piston 68 coaxially in a rearward direction between the bosses 60 and 61; the port 86 serving as a vent between annular space 65 and the hub chamber 85.

35 From the foregoing description it will be seen that the piston sleeve 69 with ring piston 68 together with exterior surface 66 of the insert and the annular bosses 60 and 61 provide a single acting hydraulic motor adapted to move the piston 67 in a rearward direction. The motor may be operated by hydraulic pressure, and means are provided to move the piston 67 in the opposite or forward direction, as described in further detail hereinafter.

40 45 As mentioned above, pin projection 78 engages a slot 79 in lever 80 and pin projection 78a engages a corresponding slot 79a in lever 80a. Lever 80 comprises an arm 87 which engages base 19 of the ferrule 17 and is securely attached there- 50 to near the periphery of the ferrule base by means of lag bolts 88; dowels 90 serving to align the lever with the ferrule. Fixed to the arm 87 is an angle arm 91 having, in its outwardly extending portion, a slot 79 which accommodates 55 the pin projection 78. With more particular reference to Figs. 2 and 3, it will be observed that when the piston 67 is moved coaxially along the insert, the pin projection also moves coaxially. When moved toward the rear under the influence 60 of hydraulic pressure the piston movement is translated to the lever since the pin engages it in the slot 79. However, the other arm 87 of the lever 80, being fixed to the base of the ferrule, the coaxial rearward movement of the piston 67 is translated to rotary motion through the lever. Thus a torque is exerted to rotate the ferrule 17, and hence the propeller blade 11, about its longitudinal axis. Blade 11a is also rotatable about its longitudinal axis in similar fashion 65 by the lever 80a when piston 67 is moved rearwardly under the influence of hydraulic pressure in annular space 64.

70 As mentioned, hydraulic pressure exerted in annular chamber 64 will drive the piston 67 rearwardly. The movement will be within the limits

of its coaxial movement as defined by the annular bosses 60 and 61. In order to provide force to move the piston from its rearward position to its forward position and at the same time to rotate the propeller blades about their longitudinal axes in the opposite angular direction from that caused by the torque exerted on them when the piston is driven by hydraulic pressure, counterweights 99 and 99a are mounted on the ferrules 11 and 11a. These weights are herein called "counterweights" for convenience of designation. Their purpose will be understood from the preceding and following description.

The counterweights are mounted in such fashion that, upon rotation of the propeller about its axis 28, centrifugal force causes the weights to exert a torque in a direction to rotate the propeller blades in a given angular direction about their respective longitudinal axes. In the illustrative embodiment disclosed in the drawings, the weights 99 and 99a are mounted to exert a torque opposed to the torque resulting from that caused by the piston 61 when the latter is under the influence of hydraulic pressure exerted on the piston. As shown in the drawings, the counterweights 99 and 99a are mounted on the ferrules 11 and 11a by means of clamp rings and are so positioned that upon rotation of the propeller about its axis 28 (clockwise as viewed from the engine) the torque exerted by the counterweights is in a direction to rotate the propeller blades 11 and 11a about their longitudinal axes toward coarse pitch position and at the same time levers 80 and 80a move the ring piston 68 to its forward position. Correlatively, hydraulic pressure in annular space 64 upon ring piston 68 sets up a torque through levers 80 and 80a in a direction to rotate the blades 11 and 11a toward fine pitch position. The means for establishing and relieving hydraulic pressure in the annular space 64 is described in further detail hereinafter.

Referring again to the counterweights 99 and 99a, they are mounted on the ferrules by clamp rings 92 and 92a. A stop arrangement is provided to control the adjustment of the propeller blades within predetermined limits for fine or coarse pitch positions. This arrangement for propeller blade 11 comprises split clamp ring 92 clamped to ferrule 11 and a lug 95 secured to the periphery of the hollow arm 16 of the hub 10. A similar arrangement is provided for blade 11a, the corresponding parts being designated by similar reference characters with sub-letters "a."

A typical clamp ring comprises a half section 55 having lugs 55 and 93 and a half section 56 having lugs 94 and 57. It will be observed that half section 56 carries as an extension of lug 57 the counterweight 99 extending in substantially radial direction from the ferrule and it should be observed that the center of gravity of the counterweight 99 for blade 11 lies to one side of the plane of rotation of the propeller, indicated by the dot-dash line 59 in Fig. 5. It will be further observed that the center of gravity of counterweight 99a for blade 11a lies to one side of the plane of rotation of the propeller and is positioned relative to weight 99 to give balance between the two propeller blades 11 and 11a.

Thus, the arrangement is such that the centers of gravity of two counterweights are located so that, upon rotation of the propeller about its axis 28 in a clockwise direction as viewed from the engine, the weights 99 and 99a will tend to follow in a circular path in a plane through the

longitudinal axes 21 and 21a of the blades, which plane is perpendicular to the propeller axis 28. Consequently, the weights will exert a torque to rotate the blades angularly on their long axes toward coarse pitch position. It may be observed also that the weights could, if desired, be adjusted to exert a torque in the opposite angular direction toward fine pitch. But for purposes of disclosure it is deemed sufficient to confine the description to the embodiment shown wherein the weights 99 and 99a normally maintain the blades in coarse pitch when the propeller is rotating at its normal speed.

The lugs 93 and 94 are maintained in predetermined fixed spaced relation by the bolts 97 and 58 which also serve to secure the clamp rings to the ferrule 11. The outwardly extending lugs 93 and 94 also provide stops which may be adjusted for fine and coarse pitch positions and cooperate with the lug 95 on the hub. It will be understood, of course, that clamp ring 92a is similarly constructed and the corresponding parts are designated by similar reference characters having the sub-letter "a."

Thus, when the stops are properly adjusted and assuming the propeller is rotating in clockwise direction as viewed in Fig. 2, the stop 94 will engage lug 95 when there is no hydraulic pressure in annular space 64 and the piston 61 is urged to its forward position on the insert through the lever mechanism 80. Likewise stop 94a will engage lug 95a. In this position the propeller blades are adjusted for coarse pitch which is their normal operating position when the propeller is rotating. On the other hand, when sufficient hydraulic pressure is exerted in space 64 against ring piston 68 to overcome the opposing force of the counterweights 99 and 99a the piston is driven to its rearward position and the propeller blades are rotated in the opposite direction about their longitudinal axes until stop 93 engages lug 95 and stop 93a engages lug 95a which is the fine pitch position (see Figs. 2 and 5).

In some cases, however, it may be desirable to place stops on the insert to cooperate with the piston of the hydraulic motor for the purpose of limiting pitch adjustment.

To move the piston 61 coaxially in a rearward direction along insert 12, there is provided a suitable pump which is preferably of rotary type mounted within the hub. As shown in the drawings, the pump 100 is of the rotary vane type (see Figs. 6 to 8). It comprises two blocks 101 and 102, one of which contains intake port 103, discharge port 104, and pressure adjusting mechanisms 105 and the other, clamped by screws 98 to the first, providing a chamber 106 to accommodate the rotor 107. The pump 100 is shaped to be mounted within the hub without interfering with the operation of the piston 61. It may be secured to the interior surface of the hub by means of screws 108. The rotor 107 is mounted eccentrically to be rotated in the rotor chamber 106. It may have radially disposed slideable vanes 109. As stated before, the hub chamber 85, provides a reservoir for hydraulic fluid; oil having been found preferable for the desired purpose.

When the rotor shaft 110 is rotated in proper direction the pump takes suction through port 103 from the reservoir provided by hub chamber 85. The oil travels through intake conduit 111, then through the rotor chamber 106, and is discharged under pressure through discharge conduit 112 and then through discharge port 104.

It will be observed that block 101 is provided with grooves 113 and 114 at the outlet and intake ports of the chamber 106. The pump discharge port 104 is connected by conduit 115 to port 84 of the hydraulic motor (see Fig. 3). Consequently, fluid pressure from the pump 100 may be exerted in annular space 64 to drive the piston 67 in a rearward direction.

To prevent building up of excess pressure on the discharge side of the pump, a relief valve 118 is provided in the block 101. It will be apparent that by suitable selection and adjustment of spring 119, pressure in conduit 112 above a predetermined amount will move the valve plug 118 out from its seat and relieve the fluid pressure through relief vent 121. The valve plug 118 is yieldably held in its seat by the spring 119 which in turn is held by a cap 122, kept in place by a split ring 123. Thus means are provided, when the pump is operating, to maintain a substantially constant fluid pressure on the discharge side of the pump and in the conduit 115 leading to the annular space 64 of the hydraulic motor.

The pump 100 is operated by means of a drive shaft 125 connected to the rotor shaft 110 by a coupling 126. Drive shaft 125 passes through a housing 127 which extends outwardly through the wall of hub barrel 15 (see Figs. 3, 5 and 9). The shaft 125 is mounted for rotation in bearings 128 and 129 mounted in the housing 127. Bearing 128 rests against an annular flange 130 maintained in place by split ring 131 and bearing 129 rests against an annular shoulder 132 and is held in place by split ring 133. To provide a seal against hydraulic fluid leaking out of the hub chamber 85, a packing ring 134 is mounted on the shaft 125 between holding rings 135 and 136. A helical spring 137 resting against a ring 137b and packer holding ring 135 urges the ring 135 against the packing 134 to insure a leak proof seal.

A friction wheel 138 is secured to shaft 125 by a nut 139 and is keyed to the shaft by a key 140. The friction wheel has a rim having an annular friction face 141 and the cup 143 within the rim provides space to accommodate the nut 139.

To cause the friction wheel 138 to rotate and consequently to drive the pump 100, there is provided a ring 150 having annular contact face 151, mounted on hub sleeve 152 for axial movement. The hub sleeve 152 extends from a fixed plate 152b bolted to bracket 14. The bore of ring 150 is provided with helical grooves 153, of which there are three equally spaced circumferentially. Keys 154, of which there are three equally spaced circumferentially about the hub sleeve 152, register with the respective grooves. Consequently, upon rotation of ring 150 on the hub 152, the ring 150 is caused to move axially on the hub. A cord 155 in an external groove 156 and fastened by a bolt 157, may be used to rotate the ring 150 from a remote place; as, for example, from the cockpit of the airplane. When the ring 150 is rotated in proper direction it may be caused to move axially toward the propeller hub and the contact face 151 will then engage the friction face 141 of the wheel 138. With the propeller rotating, the wheel 138 then will revolve in contact with face 151 in planet fashion, rotating wheel 138 to cause the pump to operate and build up pressure in conduit 115, sufficient force being established to drive the piston 67 to its rearward position against the opposing force of the weights 99 and 99a. It will

be clear from the description that with rotation of the blades upon their long axes there is a corresponding axial movement of piston 67 through the connecting levers 80 and 80a, and vice versa.

When the ring 150 is rotated in the opposite direction it will be retracted axially along the hub sleeve 152, and the ring may be moved toward the engine sufficiently to disengage the contact face 151 of ring 150 from friction face 141 of the wheel 138 and then the pump 100 will remain at rest. Hydraulic pressure in space 64 of the hydraulic motor will then be released back through the pump. To charge hydraulic fluid to the hub chamber 85, charging ports 160, closed by removable screws 161, are provided.

The operation of the device described in the foregoing is as follows: It may be assumed that the propeller assembly has been mounted on the engine as shown in the drawings. It may also be assumed that the hub barrel chamber is charged with a suitable oil of lubricating character. Also, it will have been observed that the parts have been sealed with packing material where needed and the parts otherwise joined in such fashion as to prevent oil from leaking from the propeller hub. It may be further assumed the propeller is designed for clockwise rotation as viewed from the engine.

The propeller blades 11 and 11a are adjusted to the desired coarse pitch position and the clamping rings 92 and 92a are clamped to the ferules in such manner that at coarse pitch position stop 94 engages lug 95 and stop 94a engages lug 95a. When in this position levers 80 and 80a are in such position that the piston 67 will be in its forward position. When the piston, levers and stops are in this position the propeller is adjusted for coarse pitch position and this will be the normal operating pitch position when the propeller is rotating with friction wheel 138 out of contact with ring 150. That is, ring 150 will be in its rearward position. Assuming that the propeller is rotating with the engine drive shaft in clockwise direction, viewed from the engine, the friction wheel 138 is revolving about engine drive shaft axis 28 but is not rotating on its own axis because it is out of contact with ring 150. Also, under this set of conditions there will be no substantial hydraulic pressure in annular space 64 of the hydraulic motor because the pump is at rest, that is, the rotor is not rotating on its axis although the pump 100 is revolving about the axis 28 of the propeller. Pressure in space 64 will have been relieved back through the pump. As the propeller rotates upon its axis 28, the centrifugal force of the counterweights rotating with the blades will maintain the blades in coarse pitch position with stops 94 and 94a engaging their respective lugs 95 and 95a.

If it is desired to adjust the propeller blades to fine pitch position, contact ring 150 is rotated in proper direction to cause it to be moved axially toward the propeller to bring contact face 151 into engagement with friction face 141 of wheel 138. When the propeller is rotating, this causes the wheel 138 to rotate on its own axis while it is revolving around the propeller axis 28, thus causing pump 100 to operate. Operation of pump 100 will cause it to take suction through port 103 from the reservoir of oil provided in hub chamber 85 and build up hydraulic pressure in conduit 115. Thus, fluid pressure is exerted in annular chamber 64 of the hydraulic motor against ring piston 68, which drives the

piston 67 to its rearward position against the resultant force of weights 99 and 99a and the centrifugal twisting moments of the blades 11 and 11a. When piston 67 is thus urged to its rearward position, levers 80 and 80a rotate their respective ferrules 17 and 17a until stops 93 and 93a engage their respective lugs 95 and 95a. In this position the blades are in their fine pitch position. It will be understood, of course, that the stops 93, 93a and 94, 94a of clamp rings 92 and 92a will have been adjusted to correspond with the predetermined coarse and fine pitch positions. It will also be observed that the distance between stops 93 and 94 and between 93a and 94a may be adjusted as desired for the limits of fine pitch and coarse pitch positions.

So long as the pump is maintained in operation, the ring piston 68 will be maintained in its rearward position and the propeller blades maintained in fine pitch position. Relief valve 118 of the pump 100 will prevent an excess pressure on the piston and will maintain a substantially constant pressure in conduit 115.

If it is desired to return the propeller blades to coarse pitch position, ring 150 is rotated to move it axially on hub sleeve 152 toward the engine to disengage contact face 151 from friction face 141 of pump wheel 138. When so disengaged the pump 100 will be at rest and the hydraulic pressure in annular chamber 64 of the hydraulic motor is relieved back through the pump. With no pressure exerted on the ring piston 68, the counterweights will then set up sufficient force to rotate the propeller blades 11 and 11a back to coarse pitch position and the levers 80 and 80a will return the piston 67 to its forward position which corresponds to coarse pitch position of the propeller blades. The rotating propeller will then be maintained in coarse pitch so long as the pump 100 remains at rest.

From the foregoing it will be seen that the invention provides a controllable pitch propeller which is readily adjustable for operation in two positions, namely, fine or coarse pitch. The hydraulic mechanism, comprising fluid pump, conduits, and hydraulic motor, as well as the hydraulic fluid are all within the hub and therefore it may be said that the hydraulic operating mechanism is self-contained. The counterweights are easily attached to the blades and may be readily adjusted. While the invention is adapted for large or small propellers, it lends itself particularly to the construction of smaller propellers. Inasmuch as the hydraulic operating parts are self-contained within the hub, no fluid connections are required for connection with outside pumps. Consequently, the propeller may be removed from the engine and replaced with dispatch and facility. Moreover the pump and hydraulic motor need be operated only at such times as fine pitch adjustment is desired.

Although the invention has been illustrated and described with particular reference to the embodiment shown in the drawings it will be understood that various changes, substitutions, modifications or omissions of parts may be made by those skilled in the art without departing from the invention comprehended by the following claims. It will, for example, be apparent from the foregoing description that the counterweights may be adjusted to maintain the propeller blades normally in fine pitch position when the propeller is rotating and the pump is at rest, the pump being caused to operate the piston in a direction opposed to the counterweights to move

and maintain the blades in coarse pitch position. And it will also be apparent that conduit 115 may be connected to port 86 instead of port 84 if conditions are such as to make it desirable to drive the piston 67 by hydraulic pressure to forward position instead of to rearward position as shown in the embodiment disclosed in the drawings.

What is claimed is:

1. An airplane propeller which comprises propeller blades, a hollow hub providing a reservoir for hydraulic fluid and having a plurality of radially disposed hollow arms, a protruding stop lug on each of said arms, means including a ferrule for supporting a root end of a blade in each of said arms for angular displacement about the longitudinal axis of the blade, a counterweight on each of said blades and mounted to urge angular displacement of said blades in a given direction when said propeller is rotated, a split ring clamped to each of said ferrules and securing a counterweight to the blade, said split rings each having opposing lugs adjustable away from and toward each other, one of said opposing lugs engaging one of said stop lugs when the blade is in coarse pitch position and the other of said opposing lugs engaging that stop lug when the blade is in fine pitch position, thereby providing means for limiting angular displacement of the blades, a hollow insert mounted in said hub disposed at right angles to said radially extending arms for mounting said hub on the engine driveshaft, a piston member within said hub and mounted on the exterior of said insert for slidable movement thereon, a pump mounted within said hub, means operative upon rotation of said hub to drive said pump and thereby to cause the pump to force fluid pressure against said piston to move the piston in one direction, and means connecting said piston with each propeller blade operative in response to movement of said piston to angularly displace the propeller blades about their respective longitudinal axes, said piston acting to angularly displace said blades in one direction against the force of said counterweights when said fluid pressure is exerted on said piston and said counterweights acting to angularly displace said blades in the opposite direction when said fluid pressure is released.
2. An airplane propeller which comprises propeller blades, a hollow hub barrel providing a reservoir for hydraulic fluid and having a plurality of radially disposed hollow arms, an outwardly protruding stop lug on each of said arms, means including a ferrule supporting a root end of a blade in each of said arms for angular displacement about the longitudinal axis of the blade, a split ring clamped to each ferrule, a counterweight attached to each of said split rings whereby the counterweights are mounted to urge the blades in a given angular direction upon rotation of said propeller, opposing lugs on each of the split rings and adjustable toward and away from each other and limiting the angular displacement of said blades by engagement with said stop lugs on said arms, a hollow insert mounted in said hub barrel disposed at right angles to said radially extending arms for mounting said hub on the engine driveshaft, spaced annular bosses around the exterior of said insert, a piston member mounted on the exterior of said insert for slidable coaxial movement between said bosses, a rotary pump mounted within said hub, means operative upon rotation of said hub to drive said pump, a conduit connecting said pump with the space between one of said bosses and piston to

carry fluid pressure from said pump to said space to move said piston, and lever means connecting said piston and blades to rotate said blades about their longitudinal axes in the opposite angular direction against the force of said counterweights when said piston is moved by said fluid pressure.

3. An airplane propeller which comprises propeller blades, a hollow hub barrel providing a reservoir for hydraulic fluid and having a plurality of radially disposed hollow arms, stop members on said arms, means for supporting a root end of a blade in each of said arms for angular displacement about the longitudinal axis of the blade, a counterweight attached to the root end of each blade which counterweights are mounted to urge the blades in a given angular direction upon rotation of said propeller, a hollow insert mounted in said hub barrel disposed at right angles to said radially extending arms for mounting said hub on the engine driveshaft, an hydraulic motor within said hub, a fluid pump mounted within said hub, means operative upon rotation of said propeller to drive said pump and thereby to build up fluid pressure, means including a conduit within said hub barrel to carry said fluid pressure from said pump to said motor, an adjustable spring actuated relief valve means associated with said pump to maintain a substantially constant pressure in said conduit when said pump is in operation, lever means connecting said motor and blades, said motor acting to rotate said blades in the opposite angular direction from said given direction against the force of said counterweights when said fluid pressure is exerted on said motor, and lugs connected to said counterweights engageable with said stop members providing means for limiting fine and coarse pitch of the blades.

4. A variable pitch propeller for airplanes which comprises propeller blades, a hollow hub providing a reservoir for hydraulic fluid and having radially extending arms, each arm supporting a propeller blade mounted for angular displacement about its longitudinal axis, whereby the pitch of said blade may be changed, a counterweight secured to each blade and mounted to urge its attached blade toward coarse pitch position, a rotary pump mounted within said hub for pumping hydraulic fluid contained in said reservoir, an hydraulic motor within said hub operative in response to fluid pressure exerted by said pump, pitch-changing levers within said hub connecting said motor and blades and operated by said motor to angularly displace said blades toward fine pitch position against the force of said counterweights, stop means to limit the angular displacement of said propeller blades within predetermined fine and coarse pitch positions, a hollow insert mounted in said hub to receive the driveshaft of an airplane engine for driving connection thereto, a pump drive shaft, means including a friction wheel connected to said pump driveshaft and a contact plate mounted independently of said hub to drive said pump in response to rotation of said hub; and means for moving said plate into and out of engagement with said wheel, said rotary pump, motor, pitch-changing levers and fluid all being self-contained within the interior of said hub.

5. In a changeable pitch propeller, propeller blades, a hub having arms mounting the root ends of the propeller blades for rotation of said blades about their long axes, stop members on said arms, counterweights secured to said root ends mounted to urge said blades in a given an-

gular direction to a predetermined pitch position, clamp rings securing said counterweights to the root ends of said blades, said clamp rings being angularly adjustable about the long axes of said blades, lugs on said rings providing adjustable means to engage said stop members to control the pitch limits of said blades, a hollow insert mounted in said hub for connecting the hub to the driveshaft of an engine, an annular boss on the exterior of said insert, an hydraulic motor within said hub, said motor comprising a piston engaging the exterior surface of said insert and slideable coaxially along the exterior of said insert in contact with said boss, means including levers connecting said piston and the roots of said blades to rotate said blades in the opposite direction against the force of said counterweights whereby to change the pitch of said blades to another predetermined pitch position in response to coaxial movement of said piston, a pump within said hub and having a rotatable shaft extending to the outside of said hub for producing fluid pressure, a conduit connected with said pump and motor whereby to cause fluid pumped by said pump to exert pressure on one side of said piston to cause said levers to move said blades in said opposite direction against the force of said counterweights, and means on the exterior of said hub for connection to said shaft to cause its rotation and thereby driving said pump.

6. A variable pitch propeller assembly which comprises propeller blades, a hollow hub having radially extending hollow arms; means mounting a propeller blade in each of said arms for rotation of the blade about its longitudinal axis to provide for change of the pitch of said blades; stop means for limiting angular displacement of said blades about their longitudinal axes; a hollow insert mounted in said hub to receive the drive shaft of an engine; an hydraulic motor within said hub; a fluid pump within said hub, said hollow hub providing a reservoir for fluid to be circulated by said pump; a conduit connecting said pump and motor; means causing said pump to operate when said hub is rotated by the engine shaft, thereby to cause said pump to exert fluid pressure on said motor; means including levers within said hub connecting said motor and blades to change the pitch of said blades in response to operation of said motor; said pump operating means comprising a friction wheel operatively connected to said pump; and a contact member mounted independently of said hub and movable coaxially along said drive shaft to make and break contact with said friction wheel, said friction wheel operating said pump when said propeller is rotated and said wheel is in contact with said contact member.

7. A variable pitch propeller assembly which comprises propeller blades, a hollow hub having radially extending hollow arms, means mounting a propeller blade in each of said arms for rotation about its longitudinal axis to provide for change of the pitch of said blades, pitch limit stop means for limiting the angular displacement of said blades about their longitudinal axes, a hollow insert mounted in said hub to receive the drive shaft of an airplane engine, an hydraulic motor including an annular piston in contact with the exterior surface of said insert slideable coaxially back and forth thereon, a rotary pump within said hub, said hollow hub providing a reservoir for fluid to be circulated by said pump, a pump drive shaft for said rotary pump,

13

a friction wheel mounted on said pump drive shaft, a contact ring, means mounting said ring concentrically about said engine drive shaft, said ring being rotatable and movable axially to make and break contact with said friction wheel, said pump being operated by said wheel when it contacts said ring and at rest when said wheel is out of contact with said ring, levers connecting said hydraulic motor and the ends of said blades, said motor acting to move said levers to rotate said blades to a predetermined pitch position in response to operation of said pump.

8. In a variable pitch propeller assembly, a hollow hub having radially extending hollow arms, propeller blades, means mounting a propeller blade in each of said arms for rotation about its longitudinal axis to provide for change of the pitch of said blades, stop means for limiting the angular displacement of said blades about their longitudinal axes, a hollow insert mounted in said hub to receive the drive shaft of an engine, an hydraulic motor within said hub, a fluid pump within said hub, said hollow hub providing a reservoir for fluid to be circulated by said pump, means including a friction wheel to operate said pump when said hub is rotated by the engine shaft, thereby to cause said pump to exert fluid pressure on said motor, means within said hub connecting said motor and blades to change the pitch of said blades in response to fluid pressure exerted on said motor, a hub sleeve mounted

14

independently of said propeller hub, and a rotatable contact ring mounted on said hub sleeve and movable coaxially along said drive shaft to make contact with said friction wheel, said friction wheel causing said pump to operate when in contact with said contact ring.

CHARLES I. LATHREM.
